MANUFACTURE OF ANTIKNOCK GASOLINE

Clare Kenneth Viland, Martinez, Calif., assignor
to Tide Water Associated Oil Company, San
Francisco, Calif., a corporation of Delaware

Original application October 23, 1939, Serial No.
300,727. Divided and this application August
2, 1940, Serial No. 350,038

1. Claim. (Cl. 196—11)

This invention relates to the manufacture of motor fuel by pyrolytic conversion of hydrocarbons and is more particularly concerned with the production of light motor fuel of superior quality by a combination of cracking, distillation, and polymerization processes.

It is the principal object of this invention to provide a method whereby the antiknock properties of cracked gasoline of desired volatility specifications may be substantially increased.

It is also an object of this invention to increase the yield of the total gasoline fraction obtainable by a combination of the cracking and polymerization processes.

It is a further object of the invention to provide a method whereby a thermal polymerization process, operating in conjunction with a cracking process, may be operated with greater freedom from the formation of polymer tars and coke resulting in longer periods of continuous operation without shutdowns for cleaning, repairs, etc.

Other objects will be apparent from the following description.

In the manufacture of gasoline motor fuel by the so-called cracking processes, wherein high boiling hydrocarbons are converted into lower boiling hydrocarbons by the application of high temperatures, with or without pressure, there are formed large quantities of normally gaseous hydrocarbons including hydrogen, methane, ethane, propane, propylene, butanes, and butylenes. Most of these have too high a vapor pressure to be included in marketable gasoline. However, the butanes and butylenes have sufficiently low vapor pressure that a certain percentage may be incorporated in the finished gasoline without raising the vapor pressure of the finished product above the desired value.

As commonly practiced, in the manufacture of gasoline by cracking processes, the products resulting from the cracking operation are first fractionated to obtain a raw pressure distillate of the desired end boiling point, a gas oil fraction which is generally recycled to the cracking operation, and a residual fuel oil. The raw pressure distillate is then "stabilized" by fractional distillation to remove the propane and lower boiling constituents as well as sufficient of the butanes and butylenes to leave a product of the desired vapor pressure, such as for example 8

to 10 pounds at 100° F. An alternate method of stabilization commonly employed is to remove from the raw pressure distillate the entire amount of light hydrocarbons up to and including the butanes and butylenes. From these removed light hydrocarbons a fraction consisting of butanes and butylenes is separated. A sufficient quantity of this butanes-butylenes fraction is then blended with heavier hydrocarbons of the pressure distillate to bring the vapor pressure of the latter up to the desired value.

Until recently the normally gaseous hydrocarbons resulting from the stabilization of the raw pressure distillate have found use only as refinery fuel or low priced gaseous fuel. The excess butane-butylenes has been marketed in liquid form under pressure as a cheap motor fuel. Recently it has become common practice to convert a large portion of these normally gaseous hydrocarbons into hydrocarbons of the gasoline boiling range by means of the so-called polymerization processes. As commonly employed, these polymerization processes consist briefly in subjecting the propane, propylene, butanes and butylenes to temperatures in the range of 1000° to 1300° F. whereby an increase in the olefinic content of the gases is obtained. The gases are then subjected to temperatures of about 1000 to 1150° F. at which temperatures the olefinic molecules tend to unite with other olefines to form higher boiling molecules most of which are in the gasoline boiling range. However, substantial quantities of heavy oils are also formed which have a tendency to form coke and thereby interrupt the successful operation of the plant. The formation of these heavy oils also results in the degradation to low priced fuel oil of constituents which might otherwise be manufactured into higher priced motor fuel. By proper choice of constituents fed to the polymerization process, the formation of these heavy oils can be greatly reduced with a resulting higher overall yield of the desired motor fuel.

According to the present invention a segregation of the constituents of the normally gaseous hydrocarbons is made in such a manner that the portions blended with the stabilized pressure distillate to provide the desired vapor pressure are those of the highest antiknock quality and at the same time the constituents charged

to the polymerization operation are adapted to provide maximum yields of polymerized gasoline fractions and maximum freedom from operating troubles in the operation of the polymerization plant.

Briefly, the invention may be described by reference to Figure 1 which is a schematic flow diagram of the process. Hydrocarbon oil to be cracked for the production of motor fuel is charged through line 1 into a cracking still, which is represented by cracking coil 2, wherein the oil is subjected to such temperature conditions, with or without the aid of pressure or catalysts, as to convert a substantial portion of the oil into lower boiling hydrocarbons. Such temperature may vary between 800° F. and 1300° F., depending upon the reaction time and type of charging stock as is well known in the art. The products of the cracking operation enter fractionating zone 3 which may consist of one or more fractionating towers, a series of stills, or any other suitable fractionating equipment. In the fractionating zone the products are fractionated into a plurality of fractions represented as leaving the zone through lines 4, 5, 6, 7, 8, 9, 10, and 11, in their respective order of volatility. The lightest fraction is composed of hydrogen methane, and such other light fractions which are unsuited for either blending into gasoline or for polymerization. Ordinarily this fraction will include substantially all hydrocarbons which are more volatile than propylene. This fraction leaves the fractionating zone through line 4 and is used as fuel gas or otherwise disposed of. The next lighter fraction leaves the fractionating zone through line 5 and consists essentially of propylene and propane which is well adapted as charging stock for the cracking furnace of a polymerization plant. The third fraction consists substantially of isobutane which leaves the fractionating zone through line 6. According to the invention this fraction is used as an important blending agent in the finished gasoline. It is therefore passed to storage in the gasoline storage tank 20. The next heavier fraction consisting substantially of butylenes leaves the fractionating zone through line 7. According to the invention this fraction is preferably used for charge to the polymerization plant in a special way resulting in increased yields of polymer gasoline. The fourth fraction, consisting substantially of normal butane, leaves the fractionating zone through line 8, and is added to the finished gasoline in gasoline storage tank 20. The fraction leaving through line 9 is the main body of cracked gasoline and comprises the remaining components of the cracked products which are desired in the finished gasoline. This fraction is likewise passed to the gasoline storage tank. A gas oil or recycle fraction is withdrawn through line 10 and is introduced with fresh charge entering the cracker through line 1, or if desired, this fraction may be wholly or in part disposed of in any suitable manner. The residuum from the cracking is discharged from the process through line 11.

It may be seen that the gasoline made by the process described above is composed of raw pressure distillate of the desired end boiling point which has been stabilized by the removal of propane and lighter hydrocarbons together with the removal of the butylene present. By this method of stabilization a gain in octane rating is obtained over the conventional methods in which the cracked gasoline is stabilized to the

desired vapor pressure either by eliminating the lighter of the butanes-butylenes fraction (i. e. isobutane) or by eliminating a proportional part of all the butanes-butylenes fraction. This is clearly brought out in the following Table 1 showing the octane ratings of the constituents of this fraction:

TABLE 1

Hydrocarbon	Vapor pressure @ 100° F. pounds per square inch	Octane number A. S. T. M.—D357-37T
Iso-butane.....	73	99
Butylenes.....	63	83
N. butane.....	52	91

When it is realized that the octane number of the total cracked gasoline is about 70, it is clear from Table 1 that a greater gain in octane number for a given increase in vapor pressure is realized by the addition of either isobutane or normal butane to the cracked gasoline than by the addition of butylene.

The propane-propylene fraction in line 5 together with the butylene fraction in line 7 may be passed to a polymerization plant, which may be of any type including the use of catalysts if desirable. When using the thermal polymerization process, to which the invention is preferably directed, it has been found that the yield of polymer gasoline obtained by subjecting butylenes to pyrolysis, or cracking, and polymerizing the products is far in excess of the yield obtainable from the same quantity of isobutane or butane under the same operating conditions. Thus, in eliminating the butylenes as blending stock for the cracked gasoline there is obtained a material which, while less suitable as a blending stock, is more desirable for use in the polymerization process. This is more clearly brought out in the following Table 2 which shows results obtained in a conventional thermal polymerization process when subjecting mixtures of these hydrocarbons to pyrolysis and polymerization:

TABLE 2

Yields from pyrolysis and thermal polymerization

Hydrocarbon	Barrels polymer gasoline per barrel liquefied gas charged
Propane.....	0.3
Butanes.....	0.4
Propylene.....	0.5
Butylenes.....	0.6

While the propane-propylene fraction may be mixed with the butylene fraction and the mixture charged to the pyrolytic coil of the polymerization process, or if desired, directly to the polymerization zone, the invention comprehends a novel utilization of the two fractions whereby optimum operating conditions may be obtained from the polymerization process. This feature is shown in Figure 1. The propane-propylene fraction in line 5 is conducted into a cracking or pyrolytic coil 12 maintained at a temperature sufficient to substantially increase the olefinic content of the fraction. Temperatures of the order of 1000° F. to 1300° F. are satisfactory for this purpose. However, since the fraction consists mainly of propane and propylene, higher temperatures may be used than in the case where butanes and butylenes are present. For this purpose a temperature range of between 1125° and

1300° F. is preferred to obtain optimum olefinic content of the vapors and gases discharged from pyrolytic coil. The gases issue from pyrolytic coil 12 through line 13. At this point the butylenes in line 7 may be introduced. The effect of introducing the butylenes at this point is to cool the vapors and gases issuing from coil 12 to a temperature suitable for polymerization and simultaneously to heat the butylenes to the polymerization temperature which may be from 1050° to 1150° F., a temperature of about 1100° F. being preferred. The mixture of vapors and gases in line 13, being at the desired temperature, is passed to polymerization zone 14 which may be in any desired form such as a coil or a chamber. The vapors and gases remain in zone 14 sufficiently long to produce a substantial quantity of hydrocarbons boiling within the gasoline range or so-called "Polymer gasoline." They then pass from zone 14, through line 15 into fractionating zone 16 wherein they are fractionated to produce a polymer gasoline which passes from the zone through line 19 to tank 20. The over polymerized or heavy oily fractions, undesired for gasoline, are removed through line 18, and the lighter fractions through line 17. The lighter fraction may be recycled through the process or otherwise disposed of as desired.

It is obvious to those versed in fractional distillation that absolute separation of iso-butane, butylenes, and normal butane into pure hydrocarbons is not generally commercially obtained, and that the fractions in lines 6, 7, and 8 will not generally be pure isobutane, pure butylenes, and pure normal butane respectively. Absolute fractionation is not essential to the successful operation of the process. The invention comprehends fractionation where the amount of the desired hydrocarbon recovered in each fraction is at least 75% of the amount of that hydrocarbon present in the charge to the fractionating zone.

It is also obvious that, if desired, the operation of fractionating zone 3 may be so conducted that the products obtained in streams 8 and 9 may be obtained in a single stream. Thus, the normal butane and the heavier components of the cracked gasoline may be fractionated in a single stream without departing from the spirit of the invention.

It will be apparent that at times the vapor pressure desired in the finished gasoline may be somewhat below that obtainable when blending the entire amounts of the isobutane and normal butane fractions. Under such conditions less amounts of these fractions should be used. The invention, however, contemplates that at least 75% of the total isobutane and normal butane present in the products of cracking shall be included in the finished gasoline.

The advantages of the entire system may be summarized as follows:

(a) The finished gasoline is brought up to the desired vapor pressure by blending constituents which are of highest octane rating and which are least suitable for polymerization.

(b) Material which is least suitable for blending purposes is charged to the polymerization process where it is most suitable.

(c) The pyrolytic stage of the polymerization process is relieved of the duty of converting fractions heavier than propane.

(d) Higher temperatures may be used in the pyrolytic or decomposition stage of the polymerization process resulting in higher yields of olefinic vapors and gases from the propane

charge, because the butylenes are not cracked therein.

(e) The temperature of the vapors and gases from the pyrolytic stage of the polymerization process is reduced to the desired amount for polymerization without the loss of heat.

(f) Butylene, used as a quench material for the pyrolyzed propane fractions is not subjected to undesirable pyrolysis, but is charged directly to the polymerization zone and thus assists materially in obtaining maximum gasoline yields.

(g) Yields from polymerization utilizing optimum temperatures in the pyrolytic and reaction zones as more fully described below in the preferred form of the invention may be as much as 120% of the normal yields indicated in Table 2.

(h) Conversion per pass through the equipment may be increased by as much as 20% compared to optimum conditions under conventional operation when employing the preferred form of the invention, thereby increasing capacity of the plant or reducing the size of equipment required for a given amount of product.

Figure 2 illustrates apparatus suitable for carrying out a preferred form of the invention, it being understood that in both figures valves are to be inserted at any and all parts of the system for maintaining a desired or necessary pressure, or flow. Gas and cracked gasoline from an oil cracking process enters gas separator 22 through line 21. Gas is removed from the separator 22 through line 23 and enters absorber 24 where it is stripped of substantially all propylene and heavier hydrocarbons and the stripped or fixed gas consisting essentially of ethane and lighter hydrocarbons is withdrawn from the system by line 25. Absorption oil enters the absorber by line 26 through heat exchanger 27 and cooler 28 and rich oil leaves the absorber by line 29 after absorbing substantially all propylene and heavier hydrocarbons. The absorption oil is pumped through line 29, through heat exchanger 27 into still 30, where the propylene and heavier constituents contained in the cracked gas are distilled overhead into line 31 and injected into stabilizing column 32, into which is also charged the unstable gasoline from separator 22 by means of line 33. Stabilizer 32 is operated at such pressure and temperature conditions that the overhead distillate in line 34 consists essentially of propylene, propane, and iso-butane hydrocarbons which are passed into tower 35 for further fractionation removing overhead a propylene-propane fraction through line 36 which is liquefied in cooler 37 and passed into tank 38. Any uncondensed vapors are vented from tank 38 through line 39 and reprocessed in absorber 24.

Liquefied propylene-propane in tank 38 is charged by means of pump 40 into pyrolysis or cracking furnace 41. Obviously a preheater may be used in conjunction with the pyrolysis or cracking furnace if desired. The bottom product from the stabilizing column 32 which product contains substantially all the butylenes and heavier hydrocarbons is charged through line 42 into fractionating column 43. Column 43 is operated at such pressure and temperature conditions that the gasoline is stripped of substantially all butylenes and the stripped gasoline, consisting of substantially all normal butane and heavier hydrocarbons, leaves the column through cooler 44 and line 45 and is passed into gasoline product receiving tank 46. The overhead product from tower 43, consisting of a butylene fraction, is removed by line 47 and condensed in cooler 48

75

and passed into tank 49. Any uncondensed vapors are vented from tank 49 through line 50 and reprocessed in absorber 24. The liquefied butylene fraction is pumped by means of pump 51 into the stream of pyrolyzed fractions in line 52 from furnace 41. The butylene fraction entering line 52 may or may not be heated in heater 53 before commingling with the pyrolyzed fraction, depending upon quantity and temperature of the butylene fraction, but in any case enters line 52 at temperatures substantially below cracking or polymerizing temperatures. The temperature of the pyrolyzed fractions leaving furnace 41 is so adjusted that the final temperature at the inlet to reaction zone 54 after admixture of the butylene fraction in line 52 is at the desired polymerization temperature without the further addition of heat.

Generally it has been found desirable from the standpoint of obtaining optimum polymer gasoline yields in a conventional thermal polymerization plant to adjust the temperature of pyrolyzed vapors and gases leaving the pyrolysis furnace between the limits of 1125° to 1200° F. or such temperatures depending upon the time conditions in the cracking or pyrolysis zone so that the total volumetric furnace throughput including unconverted recycle fractions when compared with the net fresh liquefied gas charge obtained from the oil cracking process through line 24 is in the ratio of between about 5 to 1 and 9 to 1. The maintaining of such furnace recycle ratios is an important factor in preventing excessive formation of incondensable gas, coke, and tars to the detriment of gasoline yields and length of runs obtainable before the plant must be shut down and cleaned out.

Under conditions of the preferred form of the invention it is now possible to increase the conversion per pass in the cracking or pyrolysis zone preceding the polymerization step by increasing conversion temperatures by 5° to 25° F. when quenching with the butylenes fraction before subjecting the combined stream to polymerization conditions so that the throughput ratio in the polymerization zone expressed as liquid volume of total charge including recycle fractions divided by the liquid volume of the fresh feed derived from the oil cracking process may be reduced to between 4 to 1 and 7 to 1 thereby increasing throughput considerably while also obtaining greater gasoline yields. In other words, due to the novel process herein not only is there less stock available for recycling due to greater conversion into valuable gasoline fractions but there is less recycle stock used which materially increases the capacity of the polymerization zone for increased yields.

The temperature of the commingled pyrolyzed propane-propylene fractions at the inlet to zone 54 may be from 1125° to 1200° F., depending upon the charging stock and the type of polymers desired; and a temperature of about 1050° to 1150° F. within the reaction or polymerization zone is preferred. The liquid polymers and gaseous fractions leaving zone 54 are treated by well-known methods for separation of liquid polymers and for recovery and recycling to furnace 41, or reaction zone 54, the normally gaseous liquefiable hydrocarbons which were unconverted in the process.

This may be further exemplified by passing such reaction products from zone 54 through line 55 into fractionating tower 56 which is operated at such temperatures and pressures that

a substantial portion of the butanes and lighter hydrocarbons are removed overhead in line 57 and passed back into absorber 24 for separation and rejection of fixed gases formed in the process.

5 The bottom product from tower 56 containing the polymer gasoline, tar and the remainder of the C₄ and lighter hydrocarbons is cooled in cooler 58 and a portion returned by means of line 59 back into line 55 as a quenching medium to stop 10 the reaction obtained in zone 54. The remainder is passed through line 60 into tower 61 where all C₄ and lighter hydrocarbons are removed overhead through line 62 and cooler 63 and received into tank 64. The uncondensed vapors from 15 tank 64 are vented by line 65 back into absorber 24 for reprocessing and the condensate removed by line 66, if consisting largely of propylene and propane, may be injected by pump 67 through line 68 back to pyrolysis furnace 41 or, if operating conditions are such that the condensate in line 66 contains substantial amounts of butanes and butylenes, the condensate is passed through line 69 back into line 21 and separator 22 for reprocessing in the gas fractionating system. The 20 bottom product from tower 61 comprising the stable polymer gasoline and polymer tars is passed through line 70 into fractionating tower 71 where polymer gasoline is removed overhead through cooler 72 and line 73 into gasoline product tank 46. Polymer tars leaving tower 71 are cooled in cooler 74 and passed through line 75 into tar product receiving tank 76.

Returning to tower 35 in which was processed the propylene-propane-isobutane fraction previously mentioned, the bottom product comprising substantially all the isobutane is cooled in cooler 77 and passed by means of line 78 into gasoline product tank 76 which then contains the (a) normal butane and all heavier gasoline products from the cracking operation first mentioned together with any normal butane product by thermal polymerization of propylene, propane or butylenes; (b) the polymer gasoline product obtained by thermal polymerization of propylene, propane, and butylenes; and (c) the isobutane fraction contained in the original cracked gas and gasoline together with any isobutane produced by thermal polymerization of propylene, propane, or butylenes.

60 The advantages to be gained by the invention from the combined operation of a cracking and polymerization plant to produce a finished gasoline of suitable vapor pressure, such as 9# Reid vapor pressure, is clearly shown by the example given in Table 3, wherein the total yield and octane number of stabilized gasoline obtainable from a typical unstabilized cracked gasoline when operating under optimum conditions in conventional methods is compared to the total yields and 65 octane number obtainable from the preferred form of the invention as outlined above in the description of Figure 2. It will be noted that, for every 1000 barrels of cracked products available for the production of finished cracked and polymer gasoline, operation under the invention results in an increased yield of 22 barrels of finished gasoline having an enhanced octane rating of 0.5 octane number over that obtainable under good practice with conventional operation. This increased yield and octane number obtainable according to the invention is equivalent to the addition of 22 barrels of 92.7 octane gasoline to the gasoline produced under conventional operation.

TABLE 3

Constituents present in total unstabilized cracked gas and gasoline, barrels	With conventional stabilizing plant charging all C ₃ and 50% of C ₄ fraction to thermal polymerization plant to make 0% gasoline			Improved operation of stabilizing and thermal polymerization plants for producing 0% gasoline as described		
	Barrels polymer gasoline	Barrels cracked gasoline	Total barrels gasoline	Barrels polymer gasoline	Barrels cracked gasoline	Total barrels gasoline

When the typical cracked distillate shown in Table 3 is stabilized according to the present invention, with the elimination of the butylenes and the retention of the iso-butane and normal butane, a stabilized cracked gasoline results which has the following composition:

Per cent by volume		
Isobutane.....	1.9	
N. Butane.....	5.5	
Iso-pentane and heavier.....	92.6	
	100.0	
Reid vapor pressure @ 100° F..... pounds.....		8.3

Due to the variations in composition of cracked distillates and accuracy of refinery fractionation

the composition of cracked gasoline stabilized according to the invention will normally fall within the following limits:

Per cent by volume
Isobutane..... 1.5-3.0
Butylenes..... 0-1.5
N. Butane..... 4.0-7.0
Iso-pentane and heavier..... 90.0-95.0

Pounds
Reid vapor pressure @ 100° F..... 7-10

While the invention is primarily directed to the manufacture of gasoline within specification limits customarily employed in carbureted automotive engines and such is the preferred embodiment, the invention is not restricted to such and the term "gasoline" used in the appended claim should be construed to include any normally liquid mixture suitable for use as a fuel for internal combustion engines of the carbureted type. The terms "propane-propylene fraction," "iso-butane fraction," "butylenes fraction," and "normal butane fraction" are used to indicate fractions predominating in the respective hydrocarbons named and containing at least 75% of the respective hydrocarbons available in the stock subjected to fractionation.

It is thus seen that the herein described operations comprise two methods of producing a finished gasoline of overlapping boiling ranges either of which provide a motor fuel of increased octane number and the products of which, when blended as in a continuous refinery operation, not only provide a finished gasoline of increased octane number, but also a greatly increased yield of such gasoline having a required vapor pressure.

This application is a division of my copending application Serial Number 300,727, filed October 23, 1939.

I claim as my invention:

In a process of making finished gasoline of desired vapor pressure from the products obtained from cracking relatively heavy hydrocarbons thus producing unstabilized gasoline, the step which comprises: fractionating an unstabilized cracked gasoline into a propane-propylene fraction, an iso-butane fraction, a butylene fraction, and a heavier gasoline fraction; heating the propane-propylene fraction to between 1125° F. and 1300° F. to increase the olefine content, mixing said butylene fraction with the thus-treated propane-propylene fraction and passing the mix-

ture through a thermal polymerization zone above 1050° F. and below the cracking temperature of the butylene fraction, stabilizing the thus-formed polymer gasoline and finally blending same with said iso-butane fraction and said heavier fraction to form a finished gasoline whereby the iso-butane fraction and the heavier gasoline frac-

tion are blended without further treatment and the butylene fraction used as a quench material for the pyrolyzed propane-propylene fraction is not subjected to undesirable pyrolysis but is charged directly into the polymerization zone, thus increasing the yield of gasoline.

CLARE KENNETH VILAND.
